UNITED STATES PATENT OFFICE.

EDWARD HASSENPLUG, OF BOSTON, MASSACHUSETTS.

IMPROVEMENT IN POCKET-BOOKS.

Specification forming part of Letters Patent No. 38,741, dated June 2, 1863.

To all whom it may concern:

Be it known that I, EDWARD HASSENPLUG, of Boston, in the county of Suffolk and State of Massachusetts, have invented a new and useful Improvement in Pocket-Books; and I do hereby declare that the following is a full, clear, and exact description of the same, reference being had to the accompanying drawings, forming a part of this specification, in which—

Figure 1 represents a perspective view of my invention when open. Fig. 2 is a front elevation of the same when closed.

Similar letters of reference in both views indicate corresponding parts.

The object of this invention is to arrange the lid or flap of a pocket-book in such a manner that the same is rendered self operating, or, more properly speaking, so that the lid closes down spontaneously whenever it has been opened and as soon as it is released.

The invention consists in the application to the sides or ends of the lid of a pocket-book of one or more springs, in combination with a stop or stops, in such a manner that on opening said lid the springs come in contact with the stop, and as soon as the lid is released it closes spontaneously, said springs being prevented by the stop from coming in such a position that they would have a tendency to open the lid instead of closing the same.

To enable others skilled in the art to make and use my invention, I will proceed to describe it.

A represents a pocket-book, made of leather or any other suitable material, with a series of pockets, *a*, to receive currency or other paper money or coin.

B is the lid, which is made out of one piece with the back of the body of the pocket-book, and which closes down over the front, as

clearly shown in Fig. 2 of the drawings. When closed it is held in place by one or more springs, *a*, which extend from the edge or edges of the lid round the ends of the body of the pocket-book, being secured to the lid and body by means of eyelets *b*, or in any other suitable manner, or, instead of using two separate springs, one strip of india-rubber may be secured to the lid and drawn across the rear side of the body of the pocket book, being retained in its place by loops or other suitable fastenings. Said spring or springs are secured to the ends of the lid and body of the pocket-book, so that on opening the lid they do not interfere with the operation of introducing new matter or of taking out some of the contents of the pocket-book.

In opening the lid the springs *a* come in contact with stops *c*, which project over its edge, as clearly shown in Fig. 1 of the drawings. Said stops may consist either of the ends of a strip of sheet metal secured to the joint of the body and lid of the pocket-book, or a simple pair of hooks may be secured to the edges of the lid, or loops or any other suitable device may be applied to produce the desired effect. On opening the lid the stops *c* prevent the springs coming in such a position that they would have a tendency to open instead of to close the lid, and as soon as the lid is released it closes spontaneously.

What I claim as new, and desire to secure by Letters Patent, is—

As a new article of manufacture, a self closing pocket-book provided with a spring or springs, *a*, and stops *c*, as shown and described.

EDWARD HASSENPLUG.
